ABSTRACT: A step-switching arrangement for changing the taps on a transformer winding without interrupting the flow of current from the winding to a load line includes a precontact switch and a current-limiting resistance connected in a series circuit extending from the transformer tap changing contacts to the load line, this circuit being paralleled by a circuit containing a changeover switch and vacuum switch connected in series and also extending from the tap-changing contacts to the load line. A circulating current through the switches and resistance and part of the transformer winding occurs during a change in taps, and this circulating current is interrupted by opening the contacts of the vacuum switch. All of the switches are actuated by hydraulic motors of the linear type, the motors being supplied from hydraulic pumps of the linear type which are operated in synchronism with the tap-changing mechanism so as to obtain the necessary operating sequence for the various switches in changing over from one tap to another.

HYDRAULIC TAP CHANGER

This invention relates to a step-switching arrangement for changing the taps on a transformer winding wherein the individual voltage steps desired by shifting from one tap to another on the winding are preselected by a step selector in conjunction with a first, or so-called "precontact" switch connected via a switchover current-limiting resistance in series therewith to the transformer load line, the series circuit connection of the precontact switch and current-limiting resistance being paralleled by another circuit containing a vacuum switch in series with a changeover switch.

A control device for step transformers is known wherein the tap can be preselected, without current, by a step selector and the uninterrupted load switching occurs by way of a switchover resistance and a vacuum switch arranged in parallel circuits to the load line, there being a mechanically actuated switch assigned to each circuit, and the control of the mechanical switches and vacuum switch being effected by a common drive by way of a suitable all mechanical transmission. However, because of the required sequential operations of the various switches, such mechanical transmissions are necessarily complicated in their design and are subject to considerable wear. In switching back and forth, as the transformer taps are changed, the two mechanically actuated switches must be operated in such sequence that the one included in the circuit in series with the switchover resistance must always be operated first as a so-called precontact while the other mechanical switch included in the circuit in series with the vacuum switch switches without current.

The object of this invention is to provide a more simple and safe solution for deriving the correct sequential operation of all three of the switches involved, that is, the precontact switch, the changeover switch and the vacuum switch by utilizing a drive which executes an oscillatory movement in the changeover of one tap to another on the transformer winding, this drive being coupled to and actuating pistons of hydraulic pumps of the linear type which are connected with double-acting hydraulic motors of the linear type whose pistons are connected respectively to the contacting actuating members of the three switches.

More particularly, the invention provides, for effecting a reciprocating movement of the working pistons coupled to the precontact and changeover switches, a symmetrically arranged pump pair coupled to the oscillatory drive, each direction of movement of the drive having assigned to it a pump which is effective for that drive direction but ineffective in the other direction of movement of the drive. The piston of the pump for effecting operation of the piston of the hydraulic motor which actuates the contacts of the vacuum switch is effective in each direction of movement of the oscillatory drive to execute a double stroke, and the piston of the hydraulic motor assigned to the vacuum switch controls, by a hydraulic connection, the piston of a control valve interposed in the hydraulic connections between the pump cylinders assigned to the hydraulic motors which actuate respectively the contacts of the precontact and changeover switches in order to effect the necessary control of these motors in relation to opening and closing operations of the contacts of the vacuum switch. In addition to a high degree of freedom in the spatial arrangement of the individual hydraulic components of the tap-changing apparatus, the vacuum switch has the further advantage, due to the constant quantity of hydraulic fluid, e.g., oil, delivered, that the opening stroke is constant and independent of any contact burnoff.

The foregoing as well as other advantages inherent in the improved tap-changing apparatus in accordance with the invention will become more apparent from the following detailed description of one suitable embodiment thereof and from the accompanying drawing the single view of which is a combined electrical and hydraulic schematic.

With reference now to the drawing, the tapped transformer winding is indicated at 1, and taps along the winding are indicated at *a* and *b*. Obviously more than this number of taps are provided along the winding but the two which have been illustrated are sufficient to explain the inventive concept. Tap *a* and others similar to it are associated with one tap selector movable contact 2, and tap *b* and others similar to it are associated with a second tap selector movable contact 3. The movable contact members 2 and 3 are associated with and move along in contact with conductor rails 2*a* and 3*a*, respectively.

Conductor rail 2*a* is connected to contact 4 of a so-called precontact switch 6, and conductor rail 3*a* is connected to contact 5 of this switch. The switch arm 6*a* pivotally mounted at 16 is movable back and forth between contacts 4 and 5 and is actuated by a piston 17 movable back and forth within cylinder 18, the latter including a slot 19 to receive the switch arm 6*a*. The switch arm 6*a* is also electrically connected through a current-limiting resistor 7 to the load line *U*.

Conductor rail 2*a* is also connected to one main switching contact 8 of a changeover switch 12, and conductor rail 3*a* is connected to another main switching contact 11 of switch 12. The switching arm 12*a* pivotally mounted at 20 is movable back-and-forth between contacts 8 and 11 and is actuated by a piston 21 movable back-and-forth within cylinder 22, the latter including a slot 23 to receive switch arm 12*a*. The switching arm 12*a* is also electrically connected through the contacts of a vacuum switch 13 to the load line *U*. The movable contact 13*a* of the vacuum switch is actuated between open and closed position by means of a piston 23 operating within cylinder 30, there being a return spring 29 within the cylinder which acts on piston 28 in the contact closing direction.

In addition to the main switching contacts 8 and 11, the changeover switch 12 includes two auxiliary contacts 9 and 10 located in the path of switch arm 12*a* between the endmost contacts 8 and 11. Connected in an auxiliary circuit with auxiliary contact 9 is a fuse 14 which connects with the circuit leading to conductor rail 2*a* and, in a similar manner, a fuse 15 is connected in an auxiliary circuit leading from auxiliary contact 10 to conductor rail 3*a*.

The step selector mechanism which moves the contact members 2 and 3 along the taps of the transformer winding is of conventional construction and hence has not been detailed as to its specific mechanism.

In order to explain the mode of operation of the step switching arrangement, the electrical schematic shows, for example, that tap selector contact 2 is on tap *a* and tap selector contact 3 is on tap *b*. Switch 6 is in the position indicated on the drawing wherein switch arm 6*a* in the solid line position is engaged with contact 4. Switch 12 is in the position indicated wherein the switch arm 12*a* in the solid line position is engaged with the main switching contact 8.

The contacts of the vacuum switch are closed and hence an electrical circuit is completed from transformer winding tap 2 to the load line *U* which can be traced from conductor rail 2*a* through switch contact 8, switch arm 12*a* and the vacuum switch 13. Another circuit to the load line *U* is completed from conductor rail 22 through switch contact 4, switch arm 6*a* and resistance 7 but this circuit will carry very little current due to the presence of resistance 7 and the fact that the circuit through switches 12 and 13 practically short circuits the circuit path through switch 6.

In order to change over from tap *a* to the next tap *b*, switch 6 is actuated to shift contact arm 6*a* from contact 4 to contact 5. This completes temporarily a circuit from conductor rail 3*a* through switch 6, resistance 7, vacuum switch 13 and switch 12 to conductor rail 2*a* thus causing a circulating current, limited by resistance 7 to flow in that part of the transformer winding between taps *a* and *b*. Assuming that vacuum switch 13 is not defective, the next step in the changeover sequence is for vacuum switch 13 to open thus interrupting the flow of circulatory current through part of the transformer winding, and

also commutating the flow of load current to line *U* from contact member 2 to contact member 3 of the tap selector. Vacuum switch 13 then recloses its contacts and the changeover switch 12 is actuated so that contact arm 12a now engages the main switching contact 11, and a direct path from tap *b* to the line *U* is completed through the series connection of the two switches 12 and 13. This completes the changeover from tap *a* to tap *b*.

The three piston-cylinder units associated respectively with the switches 6, 12 and 13 are controlled in the following manner in order to effect their required sequential operation for changing from one tap to another on the transformer winding.

An oscillatory drive plate 33 which is mounted for oscillation about an axis 35 is designed as an impulse drive, in known manner, and is coupled up to the tap selector mechanism, not shown, by which the movable contacts 2 and 3 are shifted in alternation along the taps of the transformer winding, such that drive plate 33 rotates in a clockwise direction for a change from a first to a second tap on the winding, and then in a counterclockwise direction for a change from the second to a third tap on the winding, then back in a clockwise direction, etc. thus oscillating back-and-forth for successive tap changes along the winding as indicated by arrows 34. The oscillatory drive plate 33 includes a crankpin 36 mounted upon it and to which are articulated three connecting rods 37, 38 and 39. Connecting rod 37 is articulated to piston 40 which works in cylinder 43 of a linear-type hydraulic pump, and connecting rod 39 is articulated to piston 42 which works in cylinder 45 of another linear-type hydraulic pump. Connecting rod 38 is articulated to piston 41 which works in cylinder 44 of still another linear-type hydraulic pump. The two pump units 40-43 and 42-45 are symmetrically arranged in relation to oscillation of drive plate 33 such that as the plate executes a counterclockwise movement, piston 42 will be forced into one end of cylinder 45 and piston 40 will be withdrawn from the opposite end of cylinder 43. Conversely, when drive plate 33 executes clockwise movement, piston 40 will be forced into one end of cylinder 43 and piston 42 will be withdrawn from the opposite end of cylinder 45. Piston 41, on the other hand, is located in the position shown in the drawing when crankpin 36 is in the limit position depicted and is also located in the same position when plate 33 has rotated counterclockwise to its other limit position. Piston 41 thus obviously moves into its cylinder 44 the same predetermined distance and is returned to its starting position each time plate 33 moves clockwise, or counterclockwise from one of its limit positions to the other, the piston reaching its deepest point in the cylinder at one-half the angle of oscillation of plate 33. Pump cylinder 44 is connected via an oil line 31 with the hydraulic motor cylinder 30 at the side of piston 28 opposite the biasing spring 29.

Pump cylinder 43 is permanently connected with the surrounding oil space containing the various elements of the load-switching device via port 46, and pump cylinder 45 is similarly connected with that oil space via port 47. Pump cylinder 44 is provided with a port 48 which is passed over and closed by piston 41 during each inward movement thereof. Ports 49, 50 of pump cylinders 43, 45 communicate in a direct manner via oil lines 27, 26 with the opposite ends of the hydraulic motor cylinder 18. Similarly, ports 51, 52 of pump cylinders 43, 45 communicate via oil lines 53, 54 with the opposite ends of the hydraulic motor cylinder 22 but in an indirect manner through the intermediary of a control valve including a valve piston 56 operating in a reciprocating manner within a valve cylinder 55 and oil lines 24, 25. Valve piston 56 is biased to its upper end position depicted in the drawing by a spring 57 located in the lower end of the cylinder 55 and which bears against the lower end of piston 56. The upper end of valve cylinder 55 is connected via oil line 32 with motor cylinder 30 at the side of piston 28 in which the biasing spring 29 is located.

The pump cylinders 43, 45 are also provided with overflow channels 58, 60 and 59, 61 respectively. The cylinders 18 and

22 of the hydraulic motors are mounted on and electrically insulated from a suitable support, and at least the end portions of the oil lines 24, 25 and 26, 27 terminating at these cylinders are electrically insulated therefrom since during the switching operations, switches 6 and 12 mounted on these cylinders carry different electrical potentials. Cylinder 30 is also mounted on and electrically insulated from a suitable support and at least the end portions of the oil lines 31, 32 are electrically insulated therefrom since piston 28 is connected to the movable contact 13a of the vacuum switch 13 which also carries a potential.

The required sequential operation of the hydraulic pumps and motors in changing from one tap to another on the transformer winding is as follows:

In the position depicted on the drawing, the movable contact member 2 of the tap selector mechanism is on contact *a*, as previously explained and current flow is from this tap through rail 2a, switch 12 and switch 13 in series to the load line *U*. The switchover to the next tap *b* is prepared by the movable tap selector contact 3. Drive 33 is now actuated in a counterclockwise direction indicated by the lower arrow 34. As soon as piston 42 moves inward of cylinder 45 to the point where it closes port 47, a delivery of oil takes place from this cylinder through line 26 to the right end of the hydraulic motor cylinder 18 thus shifting piston 17 to the left from the position indicated on the drawing so that switch arm 6a is rotated counterclockwise thus transferring the arm from contact 4 to contact 5. The switch arm 6a, and also switch arm 12a of switch 12 are each preferably provided with an overcenter mechanism, not illustrated, which acts in both directions of movement of the switch arms so that when the piston 17 (or piston 21) has been shifted in its cylinder for a distance corresponding to pivotal movement of the switch arm 6a (or 12a) a little more than one-half the full angle of movement of the switch arm, the overcenter mechanism takes over and quickly shifts the switch arm to its opposite end position owing to which switching at switches 6 and 12 takes place independently of any contact burnoff.

As soon as switch arm 6a arrives at contact 5, a flow of circulation current limited by resistance 7 is initiated in the manner previously explained. Meanwhile, piston 41 has now passed over and closed port 48 in cylinder 44 so that oil is now pumped from this cylinder via line 31 into cylinder 30 under the piston 28 thus actuating the movable contact member 13a of vacuum switch upward to break the contacts of this switch and thus interrupting the circulation current, and causing the load current flowing to line *U* to be commutated to the selector contact 3 via switch contact 5 and resistance 7.

As piston 28 rises in its cylinder, oil is forced via line 32 into the upper end of valve cylinder 55 to force valve piston 56 downward owing to which, at a time when vacuum switch 13 has already interrupted the circulation current, oil flows into line 25 now cleared by the valve piston 56, from pump cylinder 45 via port 52 and line 54, with ports 50 and 59 closed meanwhile, and thence into the right end of motor cylinder 22 causing displacement of piston 21 from right-to-left and actuation of switch arm 12a from contact 8 to contact 11 via contacts 9 and 10. Due to the return movement of piston 41 to the position depicted in the drawing, the contacts of vacuum switch 13 reclose under the action of the biasing spring 29 and take over the load current, thus completing a switchover from tap *a* to tap *b*.

Valve piston 56 returns to the position indicated on the drawing due to the action of the biasing spring 57. During the switching sequence described, pump cylinder 43 remains inoperative since its piston 40 is moved from the inserted position indicated in the drawing to the position corresponding to the depicted position of piston 42 of the other hydraulic pump. During the next tap changing operation in which drive plate 33 shifts back clockwise to the position depicted in the drawing, the two hydraulic pumps 42-45 and 40-43 exchange their roles in which pump 40-43 becomes the operative pump to effect a shifting of the motor piston 17 from

left-to-right in its cylinder 18 and actuation of switch arm 6a from contact 5 to contact 4.

The overflow channels 59 to 58 insure brisk working, and the overflow channel 61, or 60 serves to dampen the movement toward the end of the active stroke. If, for some reason, the contacts of the vacuum switch 13 fail to open and interrupt the circulation current, switch arm 12a shifts from contact 8 to contact 9. The arc voltage of the switching arc is then high enough for the current to reliably commutate from contact 8 to contact 9, and the circulation current is then interrupted by blowing of fuse 14 and the load current is shifted to the circuit branch containing the switchover resistance 7. Contact arm 12a then switches without current via contact 10 to contact 11. When fuse 14 responds (blows) the step switch drive is stopped and thus prevents any damage from being done to the step switch or to the transformer.

While, for the purpose of illustrated the invention, a single-phase example of construction has been illustrated, it is self-evident that the improved tap changing device can be readily applied to a three-phase embodiment, the drive 33 then being advantageously provided with three of the crankpins 36 arranged 120° apart, and the hydraulic pumps being disposed for example, in a star arrangement.

I claim:

1. In a step-switching device for changing the taps on a transformer winding connected to a load line, the combination comprising a tap selector mechanism including at least two contact members movable sequentially along different taps of the transformer winding, a precontact switch including two stationary contacts connected respectively with said movable contact members of said tap selector mechanism and a movable contact member selectively connectable with said stationary contacts, a first double-acting hydraulic motor the piston of which is connected to said movable contact member of said precontact switch, a resistance element connected between said movable contact member of said precontact switch and said load line, a changeover switch including two stationary contacts connected respectively with said movable contact members of said tap selector mechanism and a movable contact member selectively connectable with said stationary contacts, a second double-acting hydraulic motor the piston of which is connected to said movable contact member of said changeover switch, a vacuum switch connected between said movable contact member of said changeover switch and said load line, a third hydraulic motor the piston of which is connected to and controls the opening and closing of the contacts of said vacuum switch, a drive mechanism actuated in synchronism with said movable contact members of said tap selector mechanism, first and second single-acting hydraulic

5 pumps the pistons of which are connected to said drive mechanism such that said hydraulic pumps execute pumping strokes in alternation as said drive mechanism executes consecutive movements correlated to consecutive movements of said contact members of said tap selector mechanism, a first set of outlet ports from said hydraulic pumps connected via hydraulic lines directly to opposite ends of the cylinder of said first double-acting hydraulic motor, a second set of outlet ports from said hydraulic pumps connected via hydraulic lines 10 indirectly to opposite ends of the cylinder of said second double-acting hydraulic motor through a control valve, a third single-acting hydraulic pump connected to said drive mechanism such that said pump executes one pumping stroke for each movement of said drive mechanism, a hydraulic line extending 15 from an outlet port from said third hydraulic pump to the cylinder of said third hydraulic motor at one side of the piston for twice actuating the piston and the vacuum switch contacts to open and closed position for each movement of said drive mechanism, and a hydraulic line extending from the cylinder 20 of said third hydraulic motor at the other side of the piston therein to the cylinder of said control valve for actuating the piston therein to control flow of hydraulic fluid in the lines extending to the cylinder of said second double-acting hydraulic motor.

25 2. A step-switching device as defined in claim 1 for changing the taps on a transformer winding wherein said drive mechanism is arranged to effect an oscillatory movement, and wherein the pistons of said hydraulic pumps are connected with said drive mechanism by means of connecting rods articulated to a common crankpin.

30 3. A step-switching device as defined in claim 2 for changing the taps on a transformer winding wherein the connecting rod and piston of said third hydraulic pump reach dead center position at the midposition of said oscillatory drive mechanism.

35 4. A step-switching device as defined in claim 1 for changing the taps on a transformer winding and wherein said third hydraulic motor includes a biasing spring loading the piston therein to a position wherein the contacts of said vacuum switch are closed, and the admission of hydraulic fluid from said third hydraulic pump acts against the piston to open the vacuum switch contacts in opposition to said biasing spring.

40 5. A step-switching device as defined in claim 1 for changing the taps on a transformer winding wherein said control valve includes a biasing spring loading the piston therein to a position wherein fluid flow through the valve is cut off and the admission of hydraulic fluid into the valve cylinder from the cylinder of said third motor acts against the piston to open the valve in opposition to the biasing spring.
